MINING MACHINE

Taze W. Jones, Frederick, Colo., assignor of one-half to B. I. Barnes, Boulder, Colo.

Application January 31, 1944, Serial No. 520,510

6 Claims. (CL 262—28)

This invention relates to improvements in mining machines and has reference more particularly to machines of the type employed in the mining of deep veins of coal either anthracite or bituminous and which can, of course, also be used in connection with lignite or any other form of coal, as well as gypsum and shale.

Various power operated mining machines have been invented and are extensively employed for coal mining, some of these are provided with cutter bars that will undercut a coal vein and which can also be employed for making vertical cuts or kerfs so as to divide the vein into layers or squares that can be readily broken, either by means of explosives or some mechanical breaking devices.

At present the trend for home consumption of fuel is in the direction of automatic coal stokers which require coal of certain degrees of fineness and this has reduced the demand for lump coal. Where coal is mined in the form of large lumps, it must be crushed and screened in order to make it suitable for stoker use.

It is an object of this invention to produce a mining machine that will deliver the coal in substantially the proper size for stoker use and which will therefore obviate the necessity of crushing after the coal has been mined.

Another object of this invention is to produce a machine of such construction that the cutter bars or arms can be vertically adjusted so as to cut a vein of coal from the roof of the mine to the floor thereof, without the necessity of using explosives.

A further object of the invention is to produce a mining machine of the type specified in which the cutter bars or cutter head assemblies shall be so constructed that they are widest at their front ends and taper rearwardly, thereby leaving spaces on each side between the cutter chains and the vertical side walls of the kerf, which spaces will permit repairs to be effected without withdrawing the cutter head assemblies.

Another object of this invention is to produce a mining machine of the type specified in which the coal will be moved rearwardly along the center line of the kerf in position to be deposited on power operated conveyors which will remove the coal to the rear of the mining machine and deposit the same on mine cars or trucks.

A further object of this invention is to produce a mining machine of the type specified in which the mining machine can be moved longitudinally with respect to the conveyor without affecting the operation of the latter, the power

transmission being so designed as to permit operation in any relative longitudinal position.

Another object of this invention is to produce a mining machine in which the operation of the cutter head assembly can be adjusted independently of the propulsive power of the machine so as to obtain the proper relationship between the forward speed at which the cutter head assembly moves and the rate at which the cutter chains are operated.

10 A further object of this invention is to produce a mining machine of a simplified construction that can be manufactured and sold at a price within the reach of the smaller mine owners.

15 A further object of this invention is to produce a mining machine that can be adjusted to cut at any height and in which a vein of coal can be cut from the floor to the ceiling.

20 The above and any other objects that may become apparent as this description proceeds are attained by means of a construction and an arrangement of parts that will now be described in detail, and for this purpose reference will be had to the accompanying drawings in which the invention has been illustrated, and in which:

25 Figure 1 is a side elevation of the machine showing the same in operative position, some of the parts being shown in a more or less diagrammatic manner;

30 Figure 2 is a rear elevation looking in the direction of arrow 2, Figure 1;

Figure 3 is a section taken on line 3—3, Figure 4;

35 Figure 4 is a top plan view looking in the direction of arrow 4, Figure 3, parts of the machine being broken away.

Figure 5 is a section taken on line 5—5, Figure 4;

40 Figure 6 is a view looking in the direction of arrow 6, Figure 3, portions of the mechanism being indicated by broken lines; and

Figure 7 is a section taken on line 7—7, Figure 4.

45 In the drawings reference numeral 10 designates the floor of the mine, and reference numeral 11 designates ordinary mine railway rails, which support the mining machine. The construction of the machine has, to some extent, been shown in a simplified manner so as to enable the essential features to be more clearly disclosed. The frame or carriage of the mining machine consists of side members 12 and suitable transverse members 13. The wheels 14 have been shown as independently mounted on

the frame for a purpose which will hereinafter appear. Supported on the carriage is a motor 15, which, in the present embodiment, has been shown as provided with a front transmission 16 and a rear transmission 17. Gear shift levers 18 and 19 control the gear ratios in transmissions 16 and 17, respectively. Ordinary clutches may be interposed between the engine and the transmissions, if desired, in the manner in which such clutches are employed in connection with automotive vehicles. In the embodiment illustrated, power is transmitted from the motor to the horizontal transverse shafts 20 and 21 by means of suitable gears positioned in the transmission housings. These gears may be either the ordinary bevel gears, or of the worm gear type and have not been shown for the reason that such power transmissions are well known and within the knowledge of any skilled mechanician.

From shaft 20, power is transmitted to one or both of the front wheels 14, by means of a sprocket chain or belt 22.

Positioned underneath the machine carriage is a conveyor which has been outlined in a more or less diagrammatic manner. This conveyor comprises a suitable frame to the front end of which a roller 23 has been pivotally secured. To the rear end of the frame, another roller 24 has been secured. A conveyor belt 25 encircles the rollers 23 and 24 and travels in the direction of the arrow when the conveyor is operated. The conveyor may terminate in an upwardly inclined conveyor 26, whose purpose is to elevate the coal to a sufficient height to deposit it in the mine cars or trucks.

The actual construction of the conveyor frame has been purposely omitted for the sake of simplicity as it is evident that the exact details of construction of the frame is not essential to a complete understanding as such belt conveyors are well known and of many specifically different constructions.

Since it is necessary that the mining machine shall move in the direction of the length of the conveyor, while the latter remains stationary, a means for transmitting power from the shaft 21 to the conveyor which will permit this relative movement, has been shown and will now be described.

Secured to shaft 21 is a pulley 27 and secured to the under surface of the support frame member 12 are two idler pulleys 28 and 29. Another idler pulley 30 is secured to the conveyor frame. A suitable rope or V-belt or sprocket chain like that designated by reference numeral 31, passes around the drive pulley 27 and over the idler 28, thence forwardly and around the idler 30, thence rearwardly and around the pulley 32, which is connected with the drive roller 24. From here the belt returns to the drive pulley 27, after passing around the idler 29. It will be seen that by means of this belt or rope drive, the length of the belt is not affected by the relative longitudinal movement of the machine, and the conveyor and the latter can therefore remain stationary, while the mining machine advances without in any way affecting the transmission of power for the operation of the conveyor.

Secured to the frame of the machine and extending vertically are two guides 33 and 34. These guides are held in vertical position by means of diagonal braces 35 and are provided at their lower ends with forwardly extending por-

tions 36. The tops of the guide members are connected by means of a plate 37 that is secured in position by suitable bolts 38. Lifting screws 39 are journaled at the bottom and at the top in the parts designated by reference numerals 36 and 38.

Referring now more particularly to Figure 4, it will be seen that the vertical guides 33 and 34 are each provided on their front sides with dovetail slots 40 that serve as means for adjustably mounting the cutter head frame or assembly which will now be described.

The cutter head assembly has been shown as comprising a supporting frame or steel casting 41 having the general shape of a truncated isosceles triangle in the manner indicated in Figure 4. Adjacent the vertex, the frame is provided with laterally extending portions 42 having dovetail extensions 43 that engage in the slots 40. The lateral extensions are provided with notches 44 in which are positioned the nuts 45 that cooperate with the vertical screws 39.

The nuts are in the form of worm gears. A shaft 46 extends transversely and carries worms that cooperate with the worm gear nuts 45 in such a way that when shaft 46 is rotated, it imparts a simultaneous and equal rotation to the worm gear nuts, thereby raising and lowering the frame with respect to the supporting guides.

With this construction, the screws 39 are held against rotation. The rear end of the casting 41 is provided with recesses 47 in which are located the worm gears 48 which are shown most clearly in Figure 7. A drive shaft 49 extends from the motor 50 and is provided with a worm 51 that is positioned between the two worm gears 48 and operatively connected with both. Whenever shaft 49 rotates, the worm gears 48 will turn in opposite directions and at the same speed.

Vertical shafts 52 each carries a worm gear 48 that is nonrotatably connected therewith and each shaft also carries two sprocket wheels 53, one located above and the other below the worm gears 48. Cutter chains 54 are connected with the sprocket chains in the manner shown in Figure 4 and move around the frames in opposite directions as will now be described.

The front end of frame 41 is provided with vertically spaced bearing blocks 55 and 56. On opposite sides of the center line of the frame, two shafts 57 and 58 are journaled in bearings in the bearing blocks and are each provided with four sprocket wheels like those designated by reference numeral 59 in Figure 4. The cutter chains 54 extend forwardly from the sprockets 53 and thence around the two sprocket wheels at the front of the frame and thence rearwardly along the hypotenuse of the right angle triangle which they enclose as shown in Figure 4. Connecting the sprocket wheels positioned above those enclosed by the cutter chains 54 are short cutter chains 54a that extend transversely, as indicated in Figure 4. The frame 41 is provided with an elongated opening 60 through which the coal may drop onto the conveyor beneath.

Frame 41 is provided with a rearward extension that terminates in a platform 61 on which the motor 50 is supported. Motor 51 is provided with the ordinary motor controls and is of the type whose characteristics adapt it for this use.

Particular attention is directed at this point to the fact that by means of the construction shown and described, the cutter head assembly can be lowered so as to bring the lower surface 75 of the lowermost cutter chain 54 to the level

of the floor and raised to such a position that the upper surface of the uppermost transverse cutter chain 54a will be on the level with the ceiling line, which has been designated by reference numeral 62.

Since the conveyor can be retracted to such a position that the front end thereof will be to the rear of the rearmost portion of platform 61, it is possible to begin a cut at the floor level and after this has been finished the machine can then be moved rearwardly and raised so as to cut another kerf of the same thickness above and this can be continued until the top of the vein has been reached.

Referring now more particularly to Figure 4, attention is called to the shape of the cutter head assembly and to the fact that its widest portion is at the front end and that the sides slant rearwardly at a uniform rate so as to form in effect an isosceles triangle. The vertical wall of the kerf cut by the machine has been designated by reference numeral 63 and from Figure 4, it will be seen that due to the triangular shape of the cutter head assembly, there is always a substantial space between the side wall and the cutter chain and this makes it possible for the operator to enter and make repairs if occasion should require, without retracting the cutter head for this purpose.

Attention is further called to the fact that the cutter chains are moved in such a direction that the parallel sides that form the bases of the truncated right angle triangle outlined by the chains, move rearwardly and therefore the coal removed by the cutter chains will be carried rearwardly along the middle of the cutter head assembly and where this coal is above the frame it will pass through the opening 60 or the openings 64 and drop onto the conveyor located beneath.

Whenever the machine is operated in the manner shown in Figure 1, the center delivery of the coal is a desirable feature because it concentrates the stream of coal at the middle of the kerf or cut and delivers it onto the conveyor in the direction of the arrows.

In Figure 5, a transverse section taken on line 5-5, Figure 4, has been shown and in this section Z-bars 65 and especially constructed bars 66 of the shape shown have been indicated so as to give support to the chains, if this should be found desirable or necessary.

In the drawings and in this description the machine has been shown as mounted on tracks 10 and provided with flange wheels 14. This is believed to be a desirable construction, but it can be replaced by means of the ordinary caterpillar treads, if desired.

Particular attention is called to the shape of the cutter head assembly, to the unitary construction thereof and to the fact that the movement of the cutter chains and their relation to the cutter head assembly is such that the sides are always accessible in case repairs are needed and the coal is always delivered along the center line of the kerf or cut.

Particular attention is also directed to the fact that the planes of the cutter chains are horizontal instead of vertical and that for this reason the inclined sides which provide the space between the side wall 63 makes this space available for repairs, whereas if similarly shaped cutter head assemblies are operated with the planes of the cutter chains vertical, the shape would have no particular significance so far as accessibility to the parts for the purpose of repair is concerned.

Having described the invention what is claimed as new is:

1. In a mining machine two coplanar cutter chains enclosing areas of truncated right angle triangle shape, a horizontal frame for supporting the chains and means for moving said cutter chains in opposite directions with their adjacent sides traveling towards the rear whereby coal will be removed from the cut along the middle line thereof and whereby wedge-shaped spaces will be provided between the vertical walls of the kerf and the outer sides of the cutter arms.
2. In a mining machine having a supporting frame provided at its forward end with at least two spaced vertical guides, a cutter head frame connected with the guides for vertical movement, means for moving the cutter head frame vertically along the guides, the frame extending in a horizontal plane and having the general shape of a truncated isosceles triangle with its base at the front, a plurality of separate, vertically spaced pairs of kerf cutting chains carried by the frame, the chains of each pair being in coplanar relation, with their adjacent sides extending parallel with the median line of the triangle and spaced apart, and means for moving the chains in a direction to move the opposed adjacent sides rearwardly, whereby a forwardly tapering space will be formed between the vertical side walls of the kerf and the forwardly flaring sides of the cutter head frame, and whereby coal loosened by the cutter chains will be moved rearwardly along the median line of the frame.
3. In a mining machine, in combination, a supporting carriage, two spaced guides at the front of the carriage and projecting vertically therefrom, a cutter head assembly connected with the guides, for relative vertical movement, means for raising and lowering the cutter head assembly along the guides, said cutter head assembly comprising a frame of substantially truncated isosceles triangle shape, supported adjacent its vertex from the guides, in horizontal coplanar relation with its base at the front end, drive shafts journaled in the frame adjacent the support, cutter chains carried by said frame in coplanar relation and driven by said shafts in such a direction that the two chains travel rearwardly adjacent the median line of the frame, whereby coal cut by the chains will be removed from the cut along the center thereof, and means for rotating the shafts in opposite directions, comprising a worm gear on each shaft and a power driven worm positioned between and in operative engagement with both worm gears.
4. In a kerf cutting mining machine, in combination, a supporting carriage mounted for movement along the mine floor, means comprising a motor for moving the carriage, a conveyor having a conveyor belt positioned underneath the carriage, the carriage and conveyor being relatively movable in the direction of the length of the conveyor, means comprising said motor for operating the conveyor belt, said means also including a drive pulley operatively connected with the conveyor, an idler pulley secured to the conveyor and spaced from the drive pulley, a co-operating drive pulley operated by the motor, two spaced idler pulleys attached to the carriage and positioned beneath the last named drive pulley in coplanar relation thereto, and an endless power transmitting belt encircling the motor driven power pulley, the power pulley connected with the conveyor, the idler pulley connected with the conveyor and passing over the idler.

pulley connected with the carriage, whereby the carriage can be moved longitudinally with respect to the conveyor without affecting the operativeness of the means for transmitting power from the motor to the conveyor.

5. In a kerf cutting mining machine, in combination, a carriage, supporting wheels therefor, a motor supported on the carriage, means for rotating at least one of the wheels by power derived from the motor, said means comprising a speed reduction mechanism and a clutch, two vertical guide members projecting upwardly from the front end of the carriage, a cutter head assembly connected with the guide members for vertical adjustment, means for raising and lowering the cutter assembly, said assembly comprising a frame of truncated isosceles triangle shape supported in horizontal coplanar position, the base of said frame being at the front, two drive shafts operatively connected with the frame adjacent the truncated end thereof, a sprocket wheel carried by each shaft, cutter chains extending around the peripheries of the right triangular areas on each side of the median line of the frame and operatively connected with the sprocket wheels, means for rotating the sprocket wheels in opposite directions comprising worm gears connected with the shafts in coplanar relation and a worm positioned between the worm gears for transmitting motion simultaneously to both shafts to effect rotation in opposite directions, whereby the chains will be moved about their frames, the cutter chains moving rearwardly along the bases of the right triangular areas,

whereby coal removed from the cut will be delivered along the center line thereof, a conveyor positioned underneath the carriage and underneath the cutter head assembly, whereby coal removed by the cutter chains will be deposited on the conveyor.

6. In a mining machine, a cutter head assembly comprising a frame of substantially truncated isosceles triangular shape, means adjacent the vertex thereof for supporting it in horizontal position, the frame having two drive shafts adjacent the point of support, one on each side of the median line of the frame, a sprocket wheel on each shaft, a worm gear on each shaft, spaced from the sprocket wheel, a worm positioned between the worm wheels and operatively connected with both, whereby when the worm is rotated by power, the two sprocket wheels will be rotated in opposite direction, the frame having four sprocket wheels adjacent the base, positioned in a substantially straight line normal to the median line of the frame and adjacent the base thereof, there being one pair on each side of the median line, a cutter chain enclosing the three sprockets, chains on each side of the median line enclosing substantially right triangular areas, those portions of the chains that are parallel with the median line being spaced, and an auxiliary cutter chain secured to the frame in spaced parallel relation to the main chain, and two sprocket wheels for each auxiliary chain concentric with the two outer sprocket wheels of each main chain.

TAZE W. JONES.
